UNITED STATES PATENT OFFICE.

JOHN C. GEBHART, OF ST. LOUIS, MISSOURI, ASSIGNOR TO THE ECONOMETER CO., OF ST. LOUIS, MISSOURI, A CORPORATION OF MISSOURI.

DESIGN FOR A CASING FOR MEASURING-MACHINES OR THE LIKE.

51,969.

Specification for Design.

Patented Apr. 16, 1918.

Application filed November 17, 1917. Serial No. 202,660. Term of patent 14 years.

To all whom it may concern:

Be it known that I, JOHN C. GEBHART, a citizen of the United States of America, residing at St. Louis, in the State of Missouri, have invented a new, original, and ornamental Design for a Casing for Measuring-Machines or the like, of which the following is a specification, reference being had to the accompanying drawing, in which—

Figure 1 is a view in perspective from the front of the machine, and

Fig. 2 is a similar view from the rear of the machine.

I claim:

The ornamental design for a casing for measuring machines or the like, as shown.

JOHN C. GEBHART.
